BLOCKING SLED

Orley David Rogers, P.O. Box 269, W. Ludington
Drive, Farwell, Mich. 48622

Filed Oct. 15, 1971, Ser. No. 189,804

Term of patent 14 years

Int. Cl. D21—02

U.S. Cl. D34—5 K

FIG. 1

FIG. 2

FIG. 3

FIG. 4

FIG. 5

FIG. 6

FIG. 1 is a side elevational view of a blocking sled, illustrating my new design;

FIG. 2 is a top plan view of the blocking sled illustrated in FIG. 1;

FIG. 3 is a bottom plan view thereof;

FIG. 4 is a front elevational view thereof;

FIG. 5 is a rear elevational view thereof; and

FIG. 6 is a perspective view thereof.

I claim:

The ornamental design for a blocking sled, substantially as shown and described.
